UNITED STATES PATENT OFFICE.

ABEL D. TYLER, JR., OF BROCKTON, MASSACHUSETTS.

SHOE-FORM.

SPECIFICATION forming part of Letters Patent No. 643,805, dated February 20, 1900.

Application filed November 3, 1897. Serial No. 657,282. (No model.)

To all whom it may concern:

Be it known that I, ABEL D. TYLER, Jr., of Brockton, in the county of Plymouth and State of Massachusetts, have invented an Improvement in Shoe-Forms, of which the following is a specification.

Referring to the accompanying drawings, Figure 1 is a side elevation, Fig. 2 a top plan view, Fig. 3 a bottom plan view, and Fig. 4 a lengthwise central section on line 4-4 of Fig. 2, of a shoe-form embodying my invention.

The object of my invention is to produce a light-weight hollow shoe-form adapted for displaying drummers' sample shoes in an attractive manner and for keeping shoes in shape not only for display in shops and the like, but also after they pass into the hands of wearers.

My invention consists, broadly considered, in the combination of a hollow fore part having at its rear a transverse web with a heel part and a flexible connection for the fore part and heel part.

In the drawings illustrating the principle of my invention and the best mode now known to me of applying that principle the hollow fore part A is preferably made bottomless, as shown. At its rear is a transverse web a, which serves as a brace to keep the side portions or wings a' of the rear of the fore part from being crushed, bent, or warped laterally in either direction, as well as from being crushed, bent, or warped edgewise in either direction. This web a also serves as a place of attachment of the hinge connection B (preferably a leaf-hinge, as shown) to the fore part, and its rear surface a² serves as a bearing-surface for the opposed surface of the heel part D. The heel part D is preferably made hollow, as shown, without a bottom and with the transverse web d connecting its front end portions d'. The outer surface of this web d serves as a reciprocal bearing-surface for the bearing-surface a² of the fore part, the contact of these two surfaces keeping the fore part and heel part from collapsing bottomward. This brace d also serves as a place of attachment of the flexible connection B to the heel part. The webs a and d are preferably of the same height, so that if a leaf-hinge is used to articulate the fore part and heel part the leaves b of the hinge may be readily secured, respectively,

to the top surface of the webs, as shown. In any event it is highly desirable to mount the connection B in or above the line of pressure 55 between the heel and toe tending to collapse the last, so that the inherent tendency of the shoe to shorten by the upward curvature of the toe portion will not collapse the last topward. The location of the hinge also allows 60 the form to shorten when the heel part is moved upward and forward, the upper portion of the form being properly cut away to permit this shortening to facilitate the insertion and removal of the last. The leaves b 65 are preferably made with lateral projections b', which fit in cross-grooves a³ on the upper surfaces of the webs a and d, as shown. This construction facilitates the assembling of the parts and greatly relieves the fastenings b' 70 from strain and consequent tendency to work loose when the heel part is pulled to remove the form from the shoe.

This preferred form of my new shoe-form is readily made of wood, but may be made of 75 metal or various compositions. It is light in weight, yet strong and durable, and is advantageously used for carrying drummers' samples and for displaying and keeping shoes in shape.

While the form is preferably made bottomless, as shown, it may be formed with a bottom, if desired, or "bridged over" in the usual manner. The heel part may be solid, if desired.

What I claim is—

In a last, the combination of a fore part chambered from the bottom upwardly and having an integral transverse rib at its rear end, with a chambered heel part having an 90 integral transverse rib at its front end, and a hinge the leaves of which are respectively attached to said ribs; the heel part having at its rear end a thickened wall provided with a pin-hole.

In testimony whereof I have signed my name to this specification, in the presence of two subscribing witnesses, on this 21st day of October, A. D. 1897.

ABEL D. TYLER, JR.
